United States Patent Office

Des. 196,340
Patented Sept. 17, 1963

196,340

MICROPHOTOGRAPH READER

Arnis Edward Peters, La Crosse, Wis., assignor to The Microcard Reader Corporation, West Salem, Wis., a corporation of Wisconsin

Filed Feb. 11, 1963, Ser. No. 73,510

Term of patent 14 years

(Cl. D61—1)

FIG. 2

FIG. 1

Des. 196,340

PAGE 2

FIG. 3

FIG. 4

FIG. 5

FIG. 6

FIG. 1 is a perspective view of the top of a microphotograph reader embodying my new design in closed condition;

FIG. 2 is a perspective view of the bottom of the same;
FIG. 3 is a front elevational view of the same;
FIG. 4 is a rear elevational view of the same;
FIG. 5 is a side elevational view of the same; and
FIG. 6 is a top perspective view of the same in open condition.

The dotted-line portion of the grille in FIGS. 1 and 6 is so drawn to indicate repetition of the pattern.

I claim:

The ornamental design for a microphotograph reader, substantially as shown and described.
